REVERSIBLE BUCKLE

Samuel Hornreich, New York, N. Y.

Application March 12, 1952, Serial No. 276,147

1 Claim. (Cl. 24—178)

1 This invention relates to new and useful improvements in a buckle for a reversible belt.

More specifically, the present invention proposes the construction of an improved belt of the type worn about the waist to support trousers, slacks and the like having a belt body which can be worn with either face extended outward and which carries at one end a novel buckle including a pivotally mounted tongue which can be used for joining the ends of the belt body regardless of which face thereof is extended outward.

A further object of the present invention proposes characterizing the buckle by a U-shaped member to which the one end of the belt body is attached and upon which the tongue is mounted and which pivotally supports a buckle frame in a manner to be turned relative to the U-shaped frame and the tongue to face either of its sides outward depending upon which face of the belt body is extended outward.

Another object of the present invention proposes providing the free ends of the side arms of the U-shaped member with outwardly extended trunnions turnably received within complementary sockets formed in opposed sides of the buckle frame in a manner to pivotally support the buckle frame to be turned to face either side thereof outward.

As a further object, the present invention proposes providing a buckle having a rectangular buckle frame to one end of which the belt body is secured and which is provided with a tongue pivotally mounted in such a manner that the free end thereof can be pivoted through the buckle frame so that either side of the buckle frame can be faced outward.

The present invention further proposes a buckle frame to one end of which the end of the belt body and the tongue are attached with the tongue being removably attached to be interchangeable so that the free end thereof may be engaged against either face of the buckle frame.

Still further, the present invention proposes constructing the buckle to have a tongue of end aligned sections releasably joined together so that the free end section can be removed and rejoined with the pivotally mounted inner end section to have the free end section engage either face of the buckle frame.

It is a further object of the present invention to construct reversible belts of the type described which are simple and durable, which are effective for their intended purposes and which can be manufactured and sold at a reasonable cost.

2

For further comprehension of the invention, and of the objects and advantages thereof, reference will be had to the following description and accompanying drawings, and to the appended claim in which the various novel features of the invention are more particularly set forth.

On the accompanying drawings forming a material part of the present invention—

Fig. 1 is a front elevation of a reversible belt constructed in accordance with the present invention and having a portion thereof broken away.

Fig. 2 is a partial longitudinal sectional view taken on the line 2—2 of Fig. 1.

Fig. 3 is a perspective view of the U-shaped member used in the form of the invention shown in Figs. 1 and 2.

Fig. 4 is a perspective view of the buckle frame used in the form of the invention shown in Figs. 1 and 2.

Fig. 5 is a view similar to Fig. 1, but illustrating the reversible belt constructed in accordance with a modification of the present invention.

Fig. 6 is a perspective view of the tongue member used in the form of the invention shown in Fig. 5.

Fig. 7 is an elevational view of a reversible belt constructed in accordance with another modification of the present invention.

Fig. 8 is an enlarged partial longitudinal sectional view taken on the line 8—8 of Fig. 7.

Fig. 9 is a perspective view of the tongue member used in the form of the invention shown in Figs. 7 and 8.

Fig. 10 is a view similar to Fig. 7, but illustrating still another modification of the present invention.

Fig. 11 is an enlarged exploded elevational view of the tongue used in the form of the invention illustrated in Fig. 10 with a portion thereof shown in section.

The reversible belt, according to the first form of the present invention illustrated in Figs. 1 to 4, includes an elongated belt body 20 which can be worn with either face thereof extended outward. The belt body 20 is illustrated as being made of adjacent elongated strips of material 21 and 22 having adjacent ends tapered, as shown in Fig. 1, so as to facilitate the lacing of that end of the belt body 20 through the loops of a pair of trousers, slacks or the like. Adjacent their tapered ends, the adjacent strips of material are formed with aligned spaced apertures 23 for selective engagement by the tongue of a belt buckle.

The strips of material might be a strip of

decorative leather and a strip of durable decorative cloth. Suitable cloths that might be used for one of the strips of material 21 or 22 are canvas, duck or the like. With the belt body having one side formed of leather and one side formed of an ornamental cloth material, the same belt can be worn interchangeably for dress wear or sport wear. On the other hand, the strips of material 21 and 22 might be differently colored lengths of leather with one side colored black and the other side brown, permitting the same belt to be reversed for wear with a grey or blue ensemble or for wear with a brown ensemble.

The strips of material 21 and 22 forming the belt body are joined together for the major portion of their length, extended from the tapered ends thereof, by means of lines of stitches 24 extended parallel to the longitudinal side edges thereof. It is conceivable that the belt body 20 could be formed of a single elongated strip of material with both faces thereof ornamented or differently colored to be worn with either face thereof extended outward without departing from the scope and intent of the present disclosure.

The end of the belt body 20 remote from the end having the apertures 23 carries a buckle 25. The buckle 25 is constructed to include a U-shaped member 26 having an intermediate arm 26^a and a spaced side arms 26^b, as best shown in Fig. 3. The end portions of the strips of material 21 and 22 remote from the apertured ends thereof, are curled about the intermediate arm 26^a of the U-shaped member 26 from opposite sides thereof and securely attached thereto by spaced transversely extended line of stitches 27, as best shown in Fig. 2. The end portions of the strips of material 21 and 22 engaged about the intermediate arm 26^a are formed with aligned cutouts 28 which expose the center portion of the intermediate arm so that the end of a metallic tongue 29 can be freely pivotally turned about the center portion of the intermediate arm 26^a. The free end of the metallic tongue 29 is for selective engagement with one of the apertures 23 in the opposite end of the belt body 20.

Pivots supported on the free ends of the side arms 26^b of the U-shaped member 26, there is a rectangular buckle frame 30. The buckle frame 30 is made of any decorative metal such as gold, silver, stainless steel or the like. Pivotal attachment of the buckle frame 30 on the U-shaped member 26 is accomplished by means of outwardly extended and aligned trunnions 31 which are turnably extended into complementary sockets 32 formed in the opposed sides of the buckle frame 30. The reinforce the areas of the buckle frame 30 having the sockets 32, the opposed sides of the frame 30 are provided with enlarged portions 33 through which the sockets 32 are extended.

The pivotal association of the buckle frame 30 with the U-shaped member 26 permits free pivotal movement of the buckle frame 30 through 180 degrees in either direction so that the free end of the tongue 29 can be engaged with either face of the buckle frame 30. Thus, by merely turning the buckle frame 30 on the axis of the trunnions 31, the belt can be worn with either side of the belt body 20 faced outward while still leaving the tongue 29 free for selective engagement with any one of the apertures 23 securing the belt in position about the wearer's waist.

Turning now to the modification of the invention shown in Figs. 5 and 6, the construction of the reversible belt is characterized by a belt body 20 similar to that previously described. The buckle 25^c includes a rectangular elongated buckle frame 30^c about one end portion of which the end portions of the strips of material 21 and 22 are engaged. The tongue member 29^c is of T-shape, as more clearly shown in Fig. 6 and includes a tongue portion 29^a the free end of which is to be selectively engaged with one of the apertures 23. Opposite its free end, the tongue portion 29^a is integral with a cross portion 29^b provided at its ends with end aligned laterally extended trunnions 31^c. The trunnions 31^c are turnably received within complementary sockets 32^c formed in the opposed sides of the buckle frame 30^c so that the tongue member 29^c can be turned relative to the buckle member 30^c through substantially 360 degrees to engage the free end of the tongue portion 29^a with either side of buckle frame 30^c. To permit that nearly complete turning of the tongue member 29^c, the sockets 32^c are located on the side of the transverse center of the buckle frame 30^c opposed to the end portion thereof to which the belt body 20 is attached. Thus, when the tongue member 29^c is turned, the free end of the tongue portion 29^a will pass the end portion of the buckle frame 30^c to which the end of the belt body is attached, so that the belt can be worn with either side of the belt body 20 faced forward.

In all other respects, the form of the invention shown in Figs. 5 and 6 is similar to that described in connection with the first form of the invention and like reference numerals are used to identify like parts.

The modification of the invention shown in Figs. 7 to 9, is characterized by a belt body 20 similar in all details to that used in the previous forms of the invention. The buckle 25^c has a rectangular frame 30^c of elongated formation and to one end portion of which the belt body 20 is secured as described in connection with the previous forms of the invention. Pivotal and removably carried by the buckle frame 30^c, there is a tongue 29^c. The tongue 29^c is mounted on the same end portion of the buckle frame 30^c to which the belt body 20 is attached. The tongue 29^c at its attached end has a narrow strip bent into a loop portion 35 which turnably engages the end portion of the buckle frame 30^c within the cutouts 28 of the end portions of the strips of material 21 and 22 which form the belt body 20. The free end of the loop portion 35 in turn continues into a resilient finger portion 36 removably retaining the loop portion in engagement with the buckle frame 30^c.

The arrangement of the finger portion 36 permits the tongue 29^c to be disengaged from and reengaged with the buckle frame 30^c with the free end of the tongue engaging either side of the buckle frame. It will be appreciated, of course, that the face of the belt body 20 which will be worn outward will be controlled by which face of the buckle frame 30^c the free end of the tongue 29^c is engaged with.

Again, in all other respects, the modification of the invention shown in Figs. 7 to 9 is similar to that described in connection with Figs. 1 to 4 and like reference numerals are used to identify the same parts.

In the modification of the invention shown in Figs. 10 and 11, the construction of the reversible belt is essentially the same as that described in

connection with Figs. 7 to 9 differing only in the construction of the tongue 29^a forming part of the buckle 25^d. The belt body 20 is attached to the buckle frame 30^d in the same manner as described in connection with Figs. 7 to 9.

The modified tongue 29^a is of two-part construction comprising an inner end section 29^d and a free outer end section 29^e. The inner end section 29^d is smaller than the free outer end section 29^e and has a hole 37 for turnably receiving the free end portions of the buckle frame 30^d, as shown in Fig. 10. Extended in from the free end of the inner end portion 29^d, there is a concentric internally threaded bore 38. The free outer end section 29^e of the tongue 29^a is formed with a reduced externally threaded shank portion 39 arranged to be threaded into the bore 38. The adjacent ends of the sections 29^d and 29^e are of the same diameter so that when joined the tongue 29^a will be of uniform diameter throughout its length except for the end portion thereof having the hole 37.

Reversing of the belt shown in Figs. 10 and 11 is accomplished by unthreading the outer end section 29^e from the inner end section 29^d and then locating the outer end section 29^e on the desired side of the buckle frame 30^d. The shank portion 39 of the outer end section 29^e is then rethreaded into the bore 38 rejoining the sections 29^d and 29^e of the tongue 29^a.

While I have illustrated and described the preferred embodiments of my invention, it is to be understood that I do not limit myself to the precise constructions herein disclosed and the right is reserved to all changes and modifications com-

ing within the scope of the invention as defined in the appended claim.

Having thus described my invention, what I claim as new and desire to secure by United States Letters Patent is:

A reversible buckle adapted to be used with a reversible belt comprising a rectangular frame, sockets on opposite sides of the frame at the mid-points thereof, a U-shaped cross-bar member having a pair of spaced arms and a connecting cross-piece; trunnion means secured to the free ends of said arms, said trunnion means being received in said sockets to enable the frame member to pivot in a 180° arc when the belt is to be worn in reverse, said arms having a length at which said cross-piece is positionable adjacent either end of said frame, and a tongue attached to said cross-piece and having a length to engage the end of said frame opposite to that to which the cross piece is adjacent.
